UNITED STATES PATENT OFFICE.

DANIEL F. MEYER, OF CHICAGO, ILLINOIS, ASSIGNOR TO R. D. SWISHER MFG. CO.,
OF CHICAGO, ILLINOIS, A CORPORATION OF ILLINOIS.

HAND STAMP FOR CONVEX SURFACES.

Application filed January 12, 1925. Serial No. 1,736.

To all whom it may concern:

Be it known that I, DANIEL F. MEYER, a citizen of the United States of America, and a resident of Chicago, in the county of Cook 5 and State of Illinois, have invented certain new and useful Improvements in Hand Stamps for Convex Surfaces, set forth in the following specification.

My invention relates to hand stamps for 10 printing on convex surfaces, as on eggs or toys, and has for its object the production of a die cushion which will adapt itself to non-level surfaces under very slight pressure.

15 In the accompanying drawings

Fig. 1 is an elevation of a hand stamp used for dating eggs, the cushion and die being in section on line 1—1 of Fig. 2;

Fig. 2 is a plan of the die face;

20 Fig. 3 is a section on line 3—3 of Fig. 1;

Fig. 4 is a section corresponding to that shown in Fig. 1, but with the die applied to a convex surface; and

25 Fig. 5 is a section on line 5—5 of Fig. 3.

The cushion holder is a cylindrical cup 10 secured to a handle 11. The cushion is a disk 12, having on its inner face two cylindrical legs 13 and 14 separated from each other by an annular space. The inner leg 30 14 is of thinner material than the leg 13 so that it will yield more freely to a strain put upon it.

In the face of the disk 12 is a recess in which movable type 15 may or may not be 35 placed according to the use to which the stamp is to be put. To provide walls for this recess there is a bridge 16 between the walls of the inner leg 14. To brace the very thin material of the inner leg 14, there 40 are thin braces 17 shown best in Fig. 3.

The die 18 is secured to the disk 12 in the ordinary manner. If the stamp is to be used for dating purposes, then the die has

a central opening therethru as shown in Fig. 2. If the stamp is to be used for other 45 purposes, then the die simply covers the type recess, and the device operates as if there was no recess.

The cushion holder 10 is made of such 50 diameter that the cushion is a loose fit therein, and the cushion is secured by its feet to the bottom of the cushion holder, but is free at its sides. When the die is pressed against a curved surface, as shown at S in Fig. 4, the leg 13 will yield a certain amount 55 for a given pressure, but the leg 14 will yield a greater amount for the same pressure. This permits the die to accommodate itself readily to a convex surface.

The stamp shown in the drawings is one 60 adapted for dating eggs, and at the same time giving the name of the person or corporation doing the dating. As will be evident, a hand stamp serving satisfactorily for this purpose must be capable of making 65 a legible imprint on surfaces of variable contours under light pressures. This result is accomplished by the relationship of the legs of the cushion to each other, and to the 70 holder.

What I claim is:

1. A cushion for a hand stamp consisting of a plate having a recess in its face for the reception of movable type, and the back of said plate being provided with inner and outer legs, the inner leg being more yielding than the outer one. 75

2. A cushion for a hand stamp consisting of a disk having a cylindrical flange extending from the back thereof at its edge and an inner cylindrical projection of the same length and separated from the flange by an annular space, said inner projection being more yielding than the flange. 80

DANIEL F. MEYER.
